WILLIAM H. KING, OF CLINTON, MASSACHUSETTS, ASSIGNOR TO CROMPTON & KNOWLES LOOM WORKS, OF WORCESTER, MASSACHUSETTS, A CORPORATION OF MASSACHUSETTS

YIELDABLE BOBBIN SUPPORT FOR WEFT-REPLENISHING LOOMS

Application filed December 3, 1928. Serial No. 323,342.

This invention relates to improvements in bobbin supports for weft replenishing looms and it is the general object of the invention to provide a support which is yieldable in all angular directions with respect to its axis and is so held as to be yieldable under action of a force acting parallel to its axis and toward its support.

In my co-pending application Ser. No. 10 251,992, I have set forth a coil spring bobbin support comprising a single piece of wire bent on itself to be substantially cylindrical in form with preferably a conical bobbin supporting tip. A support made according to that application will yield in any angular direction with respect to the axis but no means are provided whereby the support as a whole may move along its axis when struck by a misplaced bobbin. It is a further object of my present invention to provide a holder through which the support may slide, said holder having a bore or bearing portion which serves as a sliding guide for the coils of the spring.

The support, being formed of a coil spring, tends normally to assume a position with its axis substantially straight and if deformed will exert a force tending to straighten its axis. This fact I make use of by requiring a deformation in the normal axis of the spring when the latter moves to abnormal position and relying upon the tendency of the spring to straighten its axis to restore the bobbin support to normal position.

A more specific object of my present invention is to provide a pivoted member which will act to cause a deformation in the normal axis of the spring support when the latter is acted upon by a force parallel to the axis.

Another object of my invention is to provide means for adjusting the pivoted means and also the stop for the spring support so that the latter may be given a plurality of positions in each of which it will act by its own tendency to straighten its axis to return to normal position when deformed.

With these and other objects in view which will appear as the description pro-

ceeds, my invention resides in the combination and arrangement of parts hereinafter described and set forth in the claims.

In the accompanying drawings wherein I have shown a convenient embodiment of my invention,

Fig. 1 shows a portion of a multicolor weft replenishing mechanism with my invention applied thereto,

Fig. 2 is a diagonal rear elevation looking in the direction of arrow 2, Fig. 1,

Fig. 3 is an enlarged vertical section on line 3—3 of Fig. 2,

Fig. 4 is a transverse section on line 4—4 of Fig. 3, and

Fig. 5 is a view similar to Fig. 3 but showing a modified form of the invention.

Referring to Fig. 1 it will be seen that I have provided a loom frame 10 on which is mounted a foot 11 of a multicolor magazine M. The latter is provided with a transerrer arm 12 which may be actuated in any approved manner and said magazine is provided with a plurality of guideways 13 which direct bobbins toward transfer position.

The magazine incorporates in its construction several tie rods the lower rear one of which is indicated at 14. It is to be understood that there are ordinarily four separate and independent supports to hold a bobbin in transfer position in a multicolor weft replenishing mechanism of this usual type, two of these supports being for the front side of the bobbin, one at each end, the other two being for the back of the bobbin, one at each end. While it is possible that all four of these supports may be made according to my present invention yet for the purposes of illustration I have shown but one, namely, for the back of the magazine to support the bobbin near its tip.

The rear tie rod 14 has mounted thereon a holder 20 which is held in longitudinally and angularly adjusted position with respect to the tie rod by means of a screw 21. Said holder has a bearing portion 22 provided with a bore 23 shown particularly in Fig. 3. As shown in the latter figure the upper por-

tion of the rear end of said bore is rounded as at 24 for a purpose to be described.

Said holder is provided with a threaded hole 25 preferably parallel to the bore 23 and said hole 25 receives a screw 26 which is formed with a head 27. The latter has extending transversely therethrough a pin 28 which may be held in position by a cotter pin 29 on one side and a head 30 on the other side. A wall 31 is formed as shown in Fig. 3 and is positioned to engage a web 32 formed as part of a pivoting member 33.

As shown in Fig. 2 said pivoting member is provided with spaced ears 34 through which the pin 28 extends to pivotally connect the head and member. The web 32 is so positioned that it will engage the wall 31 normally as shown in Fig. 3. The lower end of the pivoting member 33 is provided with a holding bar 36 formed preferably as an integral part of the pivoting member 33.

The bobbin support 37 is formed in a coil spring as clearly set forth in Figs. 1 and 3, the coils being closely wound together, the upper coil being formed as an eye 38 which embrace the part of the holding bar 36. The lower end of the spring 37 may be provided with a bobbin engaging tip 39 to cooperate with other bobbin supports to hold the bobbin in proper position for transfer. As shown clearly in Fig. 3 said tip may be provided with an upper threaded portion 40 which is threaded into the lower end of the spring and clamped by the coils of the latter. The coil spring 37 may be substantially the same as that shown in my aforesaid co-pending application.

The spring is made to fit snugly in the bore 23, being proportioned to slide through the latter when required to do so, but having a tight enough fit with said bore so that the bobbin tip 39 will be placed correctly to hold the bobbin in proper position.

The parts are so proportioned that under normal conditions the rear upper end of the coil spring will be held slightly out of alignment with the forward or lower portion of the spring due to the action of the holding bar 36 and the eye 38. Under normal conditions the stress set up by this slight deformation of the axis of the spring will be found sufficient to hold the bobbin support in the position shown in Fig. 3.

In operation, during a normal transfer the bobbin B will be depressed by the transferrer arm 12 and will cause a downward deflection of the spring 37 to permit the bobbin to pass into the shuttle not shown. It occasionally happens, however, that a bobbin will be misplaced with respect to the shuttle due possibly to an improper transfer and as the lay moves rearwardly the bobbin will project upwardly so as to engage the bobbin support. When this hap-

pens it is desirable to provide some form of yielding connection which will prevent breakage of the bobbin or support. This yielding is accomplished by my present invention, the support moving to the dotted 70 line position shown in Fig. 1 when subjected to an endwise pressure exerted toward the holder.

It will be seen from the dotted lines that the pivoted member 33 swings around the pin 28 as an axis, moving the holding bar in a direction transverse with respect to the normal axis of the spring 37, thereby setting up in the spring stresses which later will seek to return the spring to its normal position. When the bobbin passes out of engagement with the support so that the latter is not acted upon by the lay or any other force tending to hold the same in its abnormal position, the stress set up in the spring will tend to move the latter in a direction to relieve the stress, namely, back to the normal position. This movement will be limited by engagement of the web 32 with the wall 31. By reference to the coils 90 of the spring shown in dotted lines in Fig. 1 it will be seen that the lower portions of the coils are spaced, increasing the length of the center line of the spring, and their natural tendency to move together to shorten the center line of the spring is thought to be the reason why the spring returns to the normal position shown in full lines in Fig. 1. The return movement of the spring to its normal position is facilitated by the rounded surface 24 located on that portion of the bore 23 which is adjacent the pivot around which the eye 38 swings.

From time to time it becomes desirable to 105 adjust the position of the tip 39 and this adjustment may be effected by moving the screw 26 either into or out of the threaded hole 25, the adjustment being secured by a check nut 50.

In the modified form of the invention shown in Fig. 5 the construction is substantially the same as that found in the preferred form except that the adjustable feature is omitted. The holder 60 may be supported on the tie rod 14 and held in adjusted position by screw 61. A bore 62 similar to bore 23 extends through the holder and the spring support 63 is proportioned to have snug but sliding fit with the bore 62. 120 The rear eye 64 formed from one of the coils of the spring projects beyond the bearing 65 of the holder so as to receive the lower end of a link 66 pivoted to the holder at 67. In the modified construction the pivot around which the eye 64 swings may be located at a point intermediate the ends of the bearing 62, the effect of this relation being to cause the rear end of the spring 63 to start a rapid upward movement as soon 125 130

as end pressure is exerted on the bobbin supporting tip of the spring. As in the preferred form it is believed that the inherent resilience of the spring which tends normally to straighten the axis of said spring 5 is the force which serves to restore the support to its normal position after movement to abnormal position by a misplaced bobbin.

Experience shows that if the spring be 10 made of sufficiently strong wire it will exert considerable force in moving back to normal position. While I have shown two particular constructions which serve to deform the axis of the spring as the latter 15 receives a longitudinal movement, yet I do not wish to be limited to these forms as it is sufficient for the purposes of my present invention if the spring is acted upon by an agency tending to set up a stress therein 20 due to bending of the axis of the spring when the latter is moved to abnormal position, said stress acting when unopposed to restore the spring to normal position.

From the foregoing it will be seen that 25 I have provided a very simple form of coil spring bobbin support which will not only yield in all angular directions with respect to its axis to accommodate proper movements of the bobbin, but will also move 30 longitudinally along its axis when engaged by a misplaced bobbin and at the same time be deflected so as to set up a stress which will later act to restore the spring to its normal position by a reverse movement 35 along its axis. It will also be seen that longitudinal movement of the spring is effected without the use of additional springs or weights. It will further be seen that the end of the support opposite the bobbin end 40 gaging end of the spring is acted upon in a way to deform its axis when subject to an abnormal longitudinal pressure, and that these means set up stresses which are responsible for the return of the support to 45 its normal position.

Having thus described my invention it will be apparent that changes and modifications may be made therein by those skilled in the art without departing from the spirit 50 and scope of the invention and I do not wish to be limited to the details herein disclosed, but what I claim is:

1. In a weft replenishing mechanism, a substantially cylindrical inherently resilient 55 bobbin support movable as a unit along its axis and resisting a bending of the axis thereof, means to cause a bending of said support when the latter is moved longitudinally along its axis, and means cooperating 60 with the bent part of the support to assist the support by the inherent resilience thereof to restore the axis of the support to normal.

2. In a weft replenishing mechanism, a 65 substantially cylindrical inherently resilient

bobbin support, a fixed holder through which the support may slide, and means acting to effect bending of the support with respect to the holder when said support is subjected to an abnormal longitudinal 70 movement, said holder and bent portion of the support cooperating to restore the support to normal position.

3. In a weft replenishing mechanism, a fixed holder having a bore extending therethrough, an inherently resilient bobbin support extending through and slidably in the bore and having an axis which is normally of given form, and means acting on said support when the latter is moved relatively 75 to the bore by an abnormal force to cause the axis of the support to assume some form other than the given form to set up a stress in said support which will cooperate with the holder to tend to return the support to normal position. 80

4. In a weft replenishing mechanism, a fixed holder having a bore extending therethrough, a coil spring bobbin support having a substantially straight axis extending 90 through the bore, said support being slidably through said bore, and a connection between the spring and the holder to cause a bending of the axis of the spring when the support is subjected to an abnormal endwise 95 movement through the bore, thus setting up stresses in the spring to cause the latter to cooperate with the holder to tend to move the support to normal position.

5. In a weft replenishing mechanism, a 100 fixed holder having a bore extending therethrough, a coil spring bobbin support extending through the bore, a link supported by the holder and pivotally movable with respect to the latter and having engagement 105 with the spring, said spring being movable through the bore of the holder to cause pivotal movement of the link and the latter acting to deflect the axis of the spring.

6. In a weft replenishing mechanism, a 110 fixed holder having a bore extending therethrough, an elongated inherently resilient bobbin support slidably mounted through the bore, and a link interposed between the holder and the support and acting when said support is subjected to abnormal endwise movement to deflect the normal axis of 115 said support and thereby set up a stress which tends to return the support to normal position. 120

7. In a weft replenishing mechanism, a fixed holder having a bore extending therethrough, an elongated inherently resilient bobbin support located in and slidable with respect to the bore, a link operatively connected to the support, and means capable of assuming a plurality of positions with respect to the holder and having pivotal connection with the link, said link acting to 125 130

effect deformation of the axis of the support when the latter moves through the bore.

8. In a weft replenishing mechanism, a fixed holder having a bore extending therethrough, an elongated inherently resilient bobbin support located in and slidable with respect to the bore, a link operatively connected to the support, and means capable of assuming a plurality of positions with respect to the holder and having pivotal connection with the link, said link acting to effect deformation of the axis of the support when the latter moves through the bore, said means being movable with respect to the holder in a direction parallel to the bore.

9. In a weft replenishing mechanism, a fixed holder having a bore extending therethrough, a screw movable in the holder in a direction substantially parallel to the bore, an elongated inherently resilient bobbin support extending through and slidable with respect to the bore, and a link operatively connecting the support and screw and acting to cause a deformation of the normal axis of the elongated support when the latter moves longitudinally through the bore.

10. In a weft replenishing mechanism, a fixed holder having a bore extending therethrough, a screw normally stationary but movable in the holder in a direction substantially parallel to the bore, an elongated inherently resilient bobbin support extending through and slidable with respect to the bore, a link operatively connecting the support and screw and acting to cause a deformation of the normal axis of the elongated support when the latter moves longitudinally through the bore, and means to limit movement of the link and support in one direction.

11. A bobbin support for a weft replenishing loom including a holder having a bore therethrough, a coil spring bobbin support slidable in and extending through the bore, and means connecting the support to the holder to cause the support to move away from the axis of the bore when moved longitudinally through the bore.

12. A bobbin support for a weft replenishing loom comprising a holder having a bore therethrough, an inherently resilient elongated bobbin support slidable in and extending through the bore, and means to cause movement of a portion of the support away from the axis of the bore as the support moves longitudinally through the bore.

13. In a bobbin support for a weft replenishing loom, a holder, an inherently resilient bobbin support movable through the holder, and means to cause the inherent resilience of the support to act to return said support to normal position when moved to abnormal position through the holder.

14. In a weft replenishing mechanism, a

coil spring bobbin support normally in position to assist in supporting a bobbin, means to cause a deflection of the axis of the support simultaneously with a longitudinal motion thereof, thereby setting up a stress in the support, and fixed means against which the stress acts, the stress when acting on the fixed means tending to move the support back to normal position due to the stress caused by the deflection.

15. In a bobbin holder for a weft replenishing loom, a bobbin engaging support normally in bobbin supporting position but movable longitudinally away from such position and having a flexible portion the axis of which is normally of a given form, means to keep a part of the said axis of the given form when the support moves longitudinally along said axis away from bobbin supporting position, and additional means to deform the flexible portion so that the corresponding part of the axis is of a form other than the given form, thereby setting up a stress in the flexible portion, the means and additional means coacting with the flexible portion when the latter is under stress to return the flexible portion and axis thereof to normal when the support is free to return to normal bobbin supporting position.

16. In a weft replenishing mechanism, a bobbin support, a portion thereof being resilient and normally having a given form, said support having an axis along which it may move longitudinally, means to preserve the original form of part of the support when the support moves along its axis, and a device cooperating with the means to deflect another part of the support when said support has a longitudinal movement and tending to set up a stress in the support to return the same to normal position.

17. In a bobbin holder for a weft replenishing loom, a bobbin support having a resilient portion and movable as a whole away from bobbin supporting position, a member acting on that end of the support opposite the bobbin engaging end, a pivot for said element located at one side of the axis of the support, a guide to engage a portion of the support between the bobbin engaging end and the element and located on that side of the axis of the support adjacent the pivot, said guide assisting in determining the motion of the support away from bobbin supporting position, and a second guide located on that side of the axis of the support opposite the pivot and located between the first guide and the bobbin engaging end of the support, said support when moving away from bobbin supporting position having a portion of the axis thereof determined by said guides and having an

other part of the axis deflected by said pivoted element to produce a stress in the resilient portion of said element tending to restore the latter to normal bobbin supporting position.

5 In testimony whereof I have hereunto affixed my signature.
